UNITED STATES PATENT OFFICE.

T. CLARENCE HEISEY, OF NEWARK, OHIO, ASSIGNOR TO A. H. HEISEY & COMPANY, OF NEWARK, OHIO.

DESIGN FOR A PLATE.

Application filed March 14, 1923. Serial No. 5,467. Term of patent 14 years.

To all whom it may concern:

Be it known that I, T. CLARENCE HEISEY, a citizen of the United States of America, residing at Newark, in the county of Licking and State of Ohio, have invented a new, original, and ornamental Design for a Plate, of which the following is a specification, reference being had to the accompanying drawings, forming part thereof.

Figure 1 is a bottom plan view of a plate embodying the design of my invention.

Figure 2 is a transverse sectional view

of a portion of the plate. It is taken upon a radial-vertical line leading from the outer rim inwardly.

Figure 3 is a horizontal, sectional view of a portion of the plate. It is taken upon a circumferential-vertical line through three of the radial ribs.

I claim:

The ornamental design for a plate, as shown.

T. CLARENCE HEISEY.
